(57) **CLAIM**

The ornamental design for a running vest as shown and described.

DESCRIPTION

- FIG. 1 is a perspective view of a running vest showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top plan view thereof;
FIG. 8 is bottom plan view thereof; and,
FIG. 9 is a perspective view thereof shown in an open configuration.

The broken lines depict portions of the running vest and form no part of the claimed design.

1 Claim, 9 Drawing Sheets
